ANTENNA

William Sichak, Lyndhurst, N. J., and Salvatore Milazzo, Brooklyn, N. Y., assignors to Federal Telecommunication Laboratories, Inc., New York, N. Y., a corporation of Delaware

Application May 8, 1948, Serial No. 25,916

10 Claims. (Cl. 250—33.53)

1 This invention relates to antennas, and more particularly it relates to antennas for producing or responding to circularly polarized waves.

A principal object of the invention is to provide a high-gain omni-directional circularly polarized antenna which is particularly suitable for any system operating at a very high frequency, for example one hundred megacycles or more.

Another object is to provide a circularly polarized antenna comprised of a horizontal loop portion for producing horizontally polarized electric field components and integral vertical radiators for producing vertically polarized components, the horizontal and vertical elements being especially designed to form a rigid structural assembly and having special means for producing a predetermined phase shift between the horizontal and vertical electric field components.

Another object is to provide an antenna array consisting of a stacked-up series of antenna units, each unit comprising a horizontal loop current element and a series of vertical dipoles, the several units being spaced from each other and provided with intervening metal discs, two for each unit, to control the phase relation between the horizontal and vertical components of the electric fields from each unit.

A feature of the invention relates to a high-gain omni-directional and circularly polarized antenna which comprises a series of similar superposed units each consisting of a set of radiation elements to produce a loop current with horizontal polarization, and each unit having a plurality of stub elements or dipoles arranged symmetrically with respect to the vertical axis of the antenna. Each antenna unit is located between a pair of conductive discs which establish a ninety-degree phase difference between the horizontal and vertical electric field components.

Another feature relates to a high-gain circularly polarized antenna comprised of a series of superposed horizontal units each consisting of a series of radiators to produce horizontally polarized electric field components, all the units being supported from a central metallic supporting mast or pedestal and with each unit having a series of vertical dipoles to produce vertically polarized electric field components. In order to maintain the desired ninety-degree phase relation between the two field components, there is

2 located between each unit a circular conducting plate, the diameters of the plates being chosen so that they act as the equivalent of radial or annular wave transmission lines for decreasing the velocity of the horizontal electric field components, but without substantially delaying the vertical electric field components.

A further feature relates to a circularly polarized antenna comprised of a series of superposed horizontal units supported from a common central mast which may take the form of a co-axial transmission line. Rigidly and integrally fastened to the outer conductor of this line, at spaced intervals longitudinally of the line, are a series of horizontal dipoles arranged to form a substantially continuous radiation loop, each horizontal dipole also having rigidly attached to it a vertical dipole. Also rigidly attached to said outer conductor are a series of large diameter metal plates, each of said antenna units being located between a corresponding pair of said plates, which plates form the equivalent of a wave transmission line for producing a predetermined phase delay in the horizontal electric field components from the loops.

A further feature relates to a simplified and rugged high-gain antenna for circular or elliptical polarized waves.

The above mentioned and other features and objects of this invention and the manner of attaining them will become more apparent and the invention itself will be best understood, by reference to the following description of an embodiment of the invention taken in conjunction with the accompanying drawings, wherein:

35 Fig. 1 is an elevational view of an antenna array according to the invention.

Fig. 2 is a perspective view of one of the horizontal radiation current loop units.

Fig. 3 is a sectional view of Fig. 1 taken along the line 3—3 thereof, and viewed in the direction of the arrows.

Fig. 4 is another sectional view of Fig. 1 taken along the line 4—4 thereof, and viewed in the direction of the arrows.

It has been known heretofore that the combination of a loop antenna current and a dipole antenna current in mutually concentric relation, can be arranged to produce a circular or elliptical polarization of the radiated waves. A circularly

polarized wave may be considered as the resultant of a vertically polarized wave imposed on a horizontally polarized wave both waves travelling in the same direction. The circular polarization is obtained when the fields of the two waves are in time quadrature relation with respect to each other. In other words, at any given instant of time, the resultant field intensity vector of the vertically and horizontally polarized waves is constant in magnitude and rotates in the plane of the wave travel at synchronous speed. While, theoretically, the simplest form that such a circularly polarized antenna can take, consists of a simple horizontally disposed circular radiator or loop, and a concentric vertical radiator or dipole, it is not always feasible to obtain the desired circular polarization because of the necessity of rigidly supporting the loop and vertical dipole in fixed concentric relation. This problem is particularly difficult where an array of such units are to be supported from a common mast. Furthermore, when the antenna is to be used at very high frequencies, for example one hundred megacycles or more, the supporting mast must be metallic. This form of metallic mast may seriously affect the phase of the resultant vertically polarized radiation. In accordance with the present invention, the above-noted difficulties are overcome by providing an array of stacked-up units each consisting of horizontal loop sections and vertical dipoles which are rigidly attached to a common central tubular metal mast. In order to insure the required ninety-degree relation between the vertical and horizontal electric field components from each stacked unit, each unit is provided with a pair of large diameter metal discs or plates, so that in effect each unit is located at the central region between the spaced discs. These discs are proportioned in diameter and vertical spacing with respect to the operating frequency of the antenna, so as to produce a ninety-degree delay in the horizontal electric field components, without substantially delaying the cooperating vertical electric field components.

Thus there is shown in Fig. 1, a high-gain circularly polarized antenna comprising three stacked-up units 1, 2, 3. Since these units are preferably structurally identical, only the construction of unit 1 will be described herein. Each unit comprises a horizontal loop radiating section, one of which is shown in perspective in Fig. 2. It may comprise, for example, a central metallic hub 4 having rigidly and integrally fastened thereto a series of horizontal dipole elements 5a—5b, 6a—6b, 7a—7b. If desired, the elements 5a to 7b can be cast as an integral unit with the hub portion 4 and with their respective radial supporting spokes 8a—8b, 9a—9b, 10a—10b and preferably so that the elements 5a to 7b form a substantially complete circle except for the gaps 11, 12, 13, 14, 15, 16. The elements 5a, 6a and 7a have threaded therethrough respective bolts 17, 18, 19, which extend radially inward to a common central point within the hub 4. The hub 4 is provided with cut-out sections 20, 21, 22, through which the respective bolts pass so as to be out of direct contact with the said hub 4. The bolts 17, 18, 19, serve as excitation connectors for connecting the respective dipole elements to a common central feed conductor 23 which passes concentrically with respect to the hub 4.

Each of the horizontal dipole elements has integrally attached thereto and extending perpendicular therefrom a pair of vertical dipole elements 24a—24b, 25a—25b, 26a—26b, 27a—27b, 75

28a—28b, 29a, 29b. These vertical dipole elements can be mounted in any desired positions around the center of the antenna system, providing they are symmetrically located and equally spaced around the antenna axis. Preferably, each of the dipole elements has a length equal to one-half wavelength of the mean operating frequency of the antenna.

Each of the foregoing described units is attached by suitable fastening bolts (not shown) to a central hollow metal mast or pedestal 29 of substantially the same external diameter as the internal diameter of hub 4. The member 29 may form the outer conductor or pipe of a coaxial wave transmission line, the center conductor 23 of which extends upwardly through the units 1, 2 and 3, and can either be conductively connected to the respective bolts 17, 18, 19, of each unit, or if desired, these bolts can be capacitively coupled to the central conductor 23. Also rigidly fastened to the member 29, by suitable bolts 30, are a series of annular metal members 31, 32, 33, 34. Each of these members has attached thereto a circular metal disc or plate 35, 36, 37, 38, the discs of each pair being equally spaced above and below the ends of the corresponding dipole elements 24a to 29b. Likewise, therefore, each pair of discs is equally spaced above and below the corresponding loop elements 5a to 7b of each unit. The vertical spacing between successive discs on member 29 and their spacing with respect to the associated antenna unit and the disc diameter, will be determined by the operating frequency of the antenna. Thus each pair of discs acts as the equivalent of a radial wave transmission line of the wave guide type for the radiation from the antenna unit located therebetween. In accordance with well-known theory of wave transmission through wave guides, the horizontal component of the electric field from each antenna unit is equivalent to the case of transmission of the fundamental TE mode of vibration through an equivalent rectangular wave guide having a width equal to the spacing between the pairs of discs. Consequently, the diameters of the discs and the spacings between each pair of discs can be chosen so that the vertical electric field component and the horizontal electric field component from each of the units 1, 2, 3, are at ninety-degree phase difference. By suitable adjustment of the relative impedances of the horizontal antenna loops and the associated vertical dipoles, they can be excited with equal magnitude currents, so that the resultant radiation from each unit has a circular polarization. In other words, each pair of conductor discs decreases the velocity of the horizontal component of the electric field as it travels outwardly from the associated antenna unit but without substantially increasing the velocity of the vertical component of the electric field. In order to make sure that the excitation currents in the vertical dipole elements and the horizontal loop element of each unit are equal, the several dipole elements are chosen of suitable length and cross-section and respective spacings around the associated horizontal loop element, as is well-known in the art.

While one particular form of horizontal loop element is shown for each of the antenna units, it will be understood that any other well-known form may be employed for producing the horizontal loop current, such for example as disclosed in application Serial Number 574,879, filed Janu-

ary 27, 1945. Furthermore, while the drawing shows an antenna consisting of an array of three units, it will be understood that a greater or less number of units may be employed. Likewise, while each horizontal loop unit is shown as consisting, in effect, of three circular dipole sets, it will be understood that a greater or less number of such sets may be employed, providing the necessary substantially complete circular loop current is set up. Preferably, although not necessarily, each of the antenna units is surrounded by a cylindrical member 39 of a material which is transparent to the electric and magnetic fields of the associated antenna elements. In other words, the members 39 act as weather housings for the various antenna elements without having any effect on the electric and magnetic fields of the associated antenna unit.

While we have described above the principles of our invention in connection with specific apparatus, it is to be clearly understood that this description is made only by way of example and not as a limitation to the scope of our invention.

What is claimed is:

1. An antenna for producing substantially circularly polarized waves, comprising a plurality of coplanar antenna elements to set up electric waves polarized in said plane, other antenna elements perpendicular to and cooperating with said first antenna elements to set up electric waves polarized in a plane perpendicular to said given plane, and a pair of metal plates mid-way between which said elements are all located mounted parallel to said plane to provide essentially an effective wave guide section, and extending about said antenna elements for a distance relative to the operating wave length to produce a time quadrature phase relation between the electric fields of the waves from said elements.

2. A substantially circularly polarized antenna comprising a series of horizontal radiating elements forming an interrupted loop antenna, a conductive supporting pedestal for said antenna and substantially coaxial therewith, at least one vertically-extending antenna element being supported on said loop antenna, and a pair of metal discs mounted parallel to the plane of said loop antenna, mid-way between which the antenna is located mounted parallel to said plane to provide essentially an effective wave guide section, and extending about said antenna elements for a distance relative to the operating wave length to produce a time quadrature phase relation between the electric fields from said loop and its associated vertical antenna element.

3. An antenna system according to claim 2, in which said pedestal constitutes the outer conductor of a coaxial wave transmission line and said antenna and said discs are rigidly supported from said conductor and located symmetrically there-around.

4. A composite antenna comprising a plurality of spaced antenna units each unit including horizontal antenna elements, said elements being positioned to form substantially a closed loop, a plurality of vertical dipole elements connected respectively to said units and symmetrically located around the loop axis, a pair of spaced metal discs mid-way between which said antenna units and said dipole elements are mounted, a coaxial wave transmission line having an outer pipe conductor, means to support all said units from said pipe conductor, said means for pro-

ducing horizontal current loops comprising a series of horizontal dipole elements, and means connecting the central conductor and the pipe conductor of said transmission line respectively to the elements of said horizontal dipoles.

5. An antenna system for circularly polarized energy, comprising a series of antenna units each composed of a plurality of radiant-acting members forming a substantially symmetrical closed radiation loop in a horizontal plane, a single conductive mast along which all said units are structurally fastened in spaced relation, a plurality of vertical radiator stubs respectively, attached to the said radiant-acting members of each unit, each unit being located mid-way between a pair of metal discs whose spacing and diameter have predetermined dimensions with respect to the mean operating frequency of the antenna to produce a predetermined time delay in the waves from said radiant acting members with respect to the waves from said stub elements.

6. An antenna system according to claim 5, in which said discs are spaced apart a predetermined distance and their diameter is related to the mean operating frequency of the antenna to delay the waves from said radiant-acting members substantially ninety degrees but without substantially delaying the waves from said stub elements.

7. An antenna for circularly polarized waves, comprising a plurality of horizontal dipole elements aligned along a common vertical axis, a plurality of vertical dipole elements carried by said horizontal elements, and a pair of spaced metal discs concentric with said horizontal dipole elements positioned an equal distance on opposite sides of said horizontal elements substantially parallel with said horizontal dipole elements and forming an annular-shaped wave guide whose dimensions are related to the mean operating frequency of the antenna for producing a time phase quadrature relation between the electric fields from the horizontal and vertical dipole elements.

8. An antenna for circularly polarized waves, comprising a central conductive supporting mast, a plurality of circular metal discs concentrically attached to said mast at spaced intervals therealong, an antenna unit located mid-way between each spaced pair of discs each unit comprising a series of antenna elements surrounding said mast in a horizontal plane and a series of antenna elements surrounding said mast and parallel to said mast, said discs being spaced apart and each having a diameter related to the mean operating frequency of the antenna to cause the electric fields of the waves from said horizontal and vertical elements to be in time phase quadrature relation as they emerge from the region between the associated discs.

60 9. An antenna according to claim 8, in which a cylindrical housing is located between each successive pair of discs said housing including the corresponding antenna unit between said discs and being transparent to the radiations from said antenna units.

10. An omni-directional circularly polarized antenna, comprising a plurality of antenna elements forming a circular configuration in a horizontal plane, a plurality of vertical dipoles supported by said elements symmetrically around the common vertical axis of said elements, a pair of metal members defining a radial wave guide mid-way between which said elements and dipoles are located for omni-directional wave

transmission the dimensions of said wave guide being proportioned to effect a ninety-degree phase relation between the horizontal and vertical electric fields radiated from said wave guide.
